UNITED STATES PATENT OFFICE.

ADELBERT H. MOORE AND EDWARD F. MORTON, OF KANSAS CITY, MISSOURI, ASSIGNEES TO THE ELL-KAY MFG. CO., OF KANSAS CITY, MISSOURI, A CORPORATION OF MISSOURI.

SHEET-METAL CONSTRUCTION.

1,200,639.

Specification of Letters Patent. Patented Oct. 10, 1916.

Application filed August 23, 1915. Serial No. 46,858.

To all whom it may concern:

Be it known that we, ADELBERT H. MOORE and EDWARD F. MORTON, citizens of the United States, residing at Kansas City, in the county of Jackson and State of Missouri, have invented certain new and useful Improvements in Sheet-Metal Construction; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates to sheet metal construction and more particularly to a partition or the like, the principal object of the invention being to provide a partition or door having smooth flat faces, spaced to form a body of sufficient thickness to give it an attractive appearance and requisite rigidity, without waste of material.

In accomplishing this object we have provided the improved details of structure hereinafter described and illustrated in the accompanying drawings, wherein:

Figure I is an elevation of a partition constructed according to our invention, a part of the facing side being broken away to illustrate the interior of the body. Fig. II is a transverse section of the partition. Fig. III is an enlarged detail perspective of a corner of the partition, particularly illustrating the wood filler and its method of combination with the side member and molding. Fig. IV is an enlarged vertical section on the line IV—IV Fig. I, particularly illustrating the spacing members. Fig. V is an enlarged transverse section of the edge portion of a modified form of partition, particularly illustrating its combination with a supporting standard.

Referring more in detail to the drawing: 1—2 designate the sides of the partition, which are composed of flat sheet metal of suitable gage, having their edges inset to form shoulders 3—4 for receiving a molding strip 5; the inset being of substantially the same depth as the thickness of the molding that is applied thereto in order that when the parts are assembled a metal slab of substantially uniform thick-

ness is provided, which may be finished to represent marble or wood.

In order to provide body for the partition, to enhance its appearance and obviate buckling or bending after the partition is installed, we space the side members 1—2 apart and connect the same by braces of suitable character and number, the preferred construction of the braces constituting channel iron 7, which are fixed to one of the members, preferably by welding their bases to the inner face of said member so that the open channel faces the opposite member, any suitable number of channel iron being attached to the member, according to the size of the partition and the possible strain to which it may be exposed. In the drawings we have illustrated the channel iron 7 as extending vertically at spaced intervals across the partition, and all of channel iron secured to the same side of the partition. Fixed to the opposite partition member are angle irons 8, one leg of each of the irons being welded or otherwise securely attached to the partition member and the second leg projected into the channel member 7 on the opposite partition member, so that it is nested within the channel to prevent transverse movement of the members relative to each other, the legs of the channel and angle members being of the same width so that they coöperate in spacing the sides 1—2 apart.

The channels 7 and angles 8 are provided with slots 10—11 at intervals throughout their length and the slots in the separate members are adapted for registration to receive the transverse spacing rods 12 that are adapted for projection through the slots when the side members are assembled, to key the channel and angle members together and prevent their movement longitudinally relative to each other. The rods 12 extend to within a short distance of each vertical edge of the door and are adapted for abutment against filler blocks 14 that are located within the edges of the body between the side members 1—2 and serve the purpose of nailing strips, to which hinges, brackets or the like may be attached, and as a means for closely assembling the molding with the body of the partition. Each of the filler blocks 14 is mortised at oppo-

site edges to form shoulders that are adapted to lie against the inset portions 3-4 of the sides 1-2, and form a head 16 that lies within the body portion of the partition, and a plug 17 that projects between the lips 3-4 and into the molding 5, the extension of the plug being less than the width of the side lips of the molding, so that when screws 18 are projected through 10 the molding into the filler blocks, the molding may be drawn toward the body until its edges engage the shoulders of the side members 3-4 and the head of the block drawn outwardly against said shoulders 15 and leave a space between the outer face of the plug and the molding to provide for future adjustment. Filler blocks may be located between the channel members 7 at the upper and lower edges of the partition and the edges of the said members 1-2 may be inset or shouldered, as are the side edges, so that the molding may be arranged flush with the side members at the top and bottom, as well as at the sides, 20 25 and drawn to position as heretofore described.

The construction just described is adaptable for use as either a straight partition or a door, and it is apparent that suitable 30 hinges or other brackets may be attached to the partition although the same have not been illustrated.

In Fig. V, we have illustrated a modified form which is particularly well adapted for 35 use in connection with partitions that are carried on tubular standards. In this modification the sides 20-21 have their edges 22-23 turned back and spaced to form grooves 24-25 and an intermediate channel 26. The molding 27 is in channel form, with the legs 28-29 extending outwardly and nested between the back turned lips 22 and sides 20-21, the wood block filler 26 being located between the side members 40 45 20-21 and held in place by the transverse rod 27. With a partition of this construction the channel edge is laid against the tubular standard 28, so that a part of the standard projects into the channel and when 50 55 suitable brackets (not shown) connect the partition with the standard, a rigid construction is provided. In assembling a partition of this construction, the side members are stamped or suitably shaped to form the inset lips and the channel and angle members are spot-welded or otherwise rigidly secured to the opposite side members, in proper relation to affect the housing when the members are brought together. When 60 65 70 the parts are overlaid with the channel and angle members nested and the slots 10 in registration, the rods 12 are projected

through the registering slots to key the channel and angle members together, the ends of the rods terminating close to the 65 edges of the partition so that when the wood fillers are placed they bear against the ends of the rod. The block fillers are then located along the edges of the structure and the molding fitted over the shouldered lips 70 and the screws projected through the moldings and into the wood fillers, the tightening of the screws drawing the molding toward the body of the partition and the fillers outwardly, the edges of the molding seating 75 against the shoulders of the side members 1-2 and the head of the block seating against the shoulders of the lips 3-4. It is apparent that with this arrangement, the molding may be drawn into place and 80 should it ever become loosened it may be tightened by forcing the screws farther into the wood fillers, to reseat the members.

While we have referred to the invention as relating to a partition, it has been merely 85 for purposes of illustration and to better describe the improvement, it being apparent that the construction is adaptable for door and other sheet metal construction, as well as for straight partition work. 90

Having thus described our invention, what we claim as new therein, and desire to secure by Letters-Patent, is:—

1. A partition or the like comprising side members, apertured spacers fixed to each 95 side member and projecting in the direction of the other side member, and a key extending through apertures in the spacers on the opposite side members to hold said side members together and forming a partition 100 unit.

2. A partition or the like comprising sides, spacers fixed to the respective sides and comprising channel and angle iron members, the angle iron members having 105 parts located between the sides of the channel iron members on the opposite partition side, and means extending through the channel and angle iron members for holding the same together and forming a unit 110 of the separate partition sides.

3. A partition or the like comprising sides, one having channel members and the other angle members fixed thereto and each adapted for nesting with a mating member 115 on the opposite side, the channel and angle members having registering slots, rods extending through said slots, and edge molding closing the spaced edges of the structure.

In testimony whereof we affix our signatures.

ADELBERT H. MOORE.
EDWARD F. MORTON.
